UNITED STATES PATENT OFFICE

2,578,180

SCRUBBER WITH LINING AND PADDLES OF RUBBERY MATERIALS

Ray C. Edwards, Wauwatosa, Wis., assignor to Allis-Chalmers Manufacturing Company, Milwaukee, Wis., a corporation of Delaware

Application September 2, 1948, Serial No. 47,428

2 Claims. (Cl. 241—102)

1

This invention relates to devices for treating granular materials to effect separation therefrom of adherent foreign substances without breaking down the granular material. More particularly it concerns an improved apparatus for scrubbing grains of material against one another under pressure to cause such separation.

Devices are known to the prior art in which granular materials are tumbled together to effect such separation of adherent substances therefrom, and there are some known devices in which pressure is exerted upon the granular material by relatively moving surfaces during treatment.

In metal foundry practice articles having interior surfaces are cast in molds having cores of sand mixed with various binders which upon baking render the core strong and resistant to disintegration during the pouring operation. The binder is of such a character that it is carbonized or otherwise burned by the heat of the molten metal after pouring so that the core may be readily disintegrated for removal.

When the cores are removed, the sand grains are covered with a tenacious deposit of burned oils or other binders and cannot be reused to form strong cores unless reclaimed by some process which will remove this deposit.

Used sand has been reclaimed in the past by various processes, some involving machines for mulling the sand under certain conditions to cause a release of the grains from the tenacious deposits of foreign materials. It is desirable in this and other mulling operations for release of granular materials from tenacious surface deposits to avoid breaking down or comminution of the sand or other particles which are to be recovered as a product.

The present invention has as an object the creation of a novel apparatus for mulling granular materials which will effectively and efficiently release the grains from surface deposits.

It is a further object of this invention to provide a novel scrubber which may advantageously be used in reclamation of foundry sands and more particularly core sand.

More specifically the invention concerns mulling the granular material to be treated in a receptacle lined with a rubbery material, using a muller faced with a rubbery material, moving relative to, and biased to move in a direction toward such lining of rubbery material in a manner to create pressure against the material between the muller and lining surfaces.

Still more particularly, the invention is concerned with providing a continuously operated

2

mulling machine having a stationary drum and a single continuously rotated muller rotor.

The invention having the above and still further objects and advantages which will become apparent from a reading hereof, may best be carried into practical effect as described herein with reference to the drawing, in which:

Fig. 1 is a vertical sectional view of a simple form of apparatus embodying certain features of the present invention.

Fig. 2 is a side view partially in vertical, longitudinal section of a preferred machine according to the present invention.

Fig. 3 is a cross section taken on line III—III of Fig. 2.

Like reference characters indicate the same or similar parts throughout the several views.

The simplest possible form of device embodying at least one feature of the present invention is illustrated in Fig. 1 of the drawing and consists of an open topped, round container 1 with a rubber lining 2 constituting a work supporting surface. The container is mounted upon a base 3 from which a pedestal 4 projects upwardly extending over the open top of the container 1. Pedestal 4 rotatably supports a rotating shaft 6, driven by a motor 7 through bevel gears 8 and 9. At the lower end of shaft 6, near the bottom of container 1, is a muller 11 having a pair of flexible muller arms 12 of rubbery material which are rotated with shaft 6 and have their ends thrust outwardly toward the lining 2 by centrifugal force during rotation. The construction of the rotor 11 and arms 12 will be clear from a description of similar parts of the preferred embodiment described hereinbelow.

The preferred embodiment of the present invention is shown in Figs. 2 and 3 of the drawing. In this form a tubular container 21 is mounted on a framework 22, one end of which is pivoted at 23 to a suitable foundation 23 and the other end of which is supported by an adjusting screw arrangement 24 of suitable known construction. Pedestal bearings 26 and 27, at opposite ends of the frame 22, rotatably support a shaft 28 driven through a suitable power transmission mechanism 29 by an electric motor 31 which may be mounted on frame 22.

Tubular container member 21 may be closed at its higher or feed end as by a cover 32 supporting a feed conveyor 33 and hopper 34 through which materials to be treated may be introduced into the feed end of the member 21. At the lower end of member 21, the discharge chute 36 is arranged to direct treated materials to a suitable point of

use, in an obvious manner. The tubular member 21 is lined with a heavy coating 37 of resilient, tough, rubbery material forming a resilient work supporting surface.

Shaft 28 is made square between its journal portions, and is equipped with a series of pairs of muller arms each pair displaced by ninety degrees from the adjacent pair on either side. The muller arms are each composed, for example, of a plate 38 welded to shaft 28 and projecting to one side, and a flap 39 of thick rubbery material secured to the plate 38 and extending outwardly tangent to the shaft. It will be seen from the drawing that the muller arm flaps 39 are of such length radially of the shaft that the tips of a pair of such flaps would normally extend in opposite directions to a diameter exceeding the internal diameter of the tubular member 21 or its lining 37, in which they are to be used, so that when inserted in the tubular member, the flaps must be flexed in a radial plane. Rotation of shaft 28 in the direction of the arrow 41 in Fig. 3 will cause the flaps 39 to flex in a sense opposite the direction of rotation, their tips dragging in frictional engagement with the lining 37 and being thrust outwardly by centrifugal force. The flaps of each pair of muller arms will, of course, extend in opposite directions relative to the shaft 28 to balance each other.

The muller arms of the device of Fig. 1 are of construction similar to those of Figs. 2 and 3, the arms 12 corresponding to flaps 39.

In order to provide for development of the desired forces, each flap 39 (or arm 12) may be provided with a weight bar 42 suitably secured to the rearward side of the flap tip. Rotation of the shaft 28 will cause centrifugal force to be exerted on the weight bars 42 increasing the pressure between the flap tips and the rubber lining 37 (2) for reasons set forth hereinafter.

Operation of the device of Fig. 1 is of course, quite simple. A charge of material to be treated is inserted in the open top of container 1, the rotor is turned, and arms 12 fly out under the influence of centrifugal force, agitating the material in container 1 and forcing the particles to move against each other. Particles caught between the tips of arms 12 and the surface of lining 2 will be milled under pressure, and tenacious surface deposits will be loosened therefrom by impact and attrition between the grains. Action of the rubbery surfaces themselves will of course not cause any substantial degradation or comminution of materials and the net result will be a loosening and removal of surface deposits from the grains under treatment.

The device of Figs. 2 and 3 is operated by rotating shaft 28 in the direction shown by the arrow in Fig. 3 and supplying material, such as used core sand, ore particles with tenacious surface deposits, or other granular material to be treated, to the hopper 34, whence it is conveyed by feed conveyor 33 to the interior of tubular member 21 near its higher end. The first pair of flaps 39 rotating in an inclined plane will strike the material, agitating the same and scrubbing the particles against each other under pressure between the rubbery surfaces of the tips of flaps 39 and lining 37, and since the material particles will be moved by the flaps in an inclined plane, and will fall under the influence of gravity when not being so moved, the particles will be gradually advanced toward the lower end of the drum 21 by the action of the flaps or paddles and gravity, and will ultimately be discharged at chute 36.

Continuous feed of material at 34 will result in continuous operation of the apparatus upon a stream of material in container member 21. The rate of feed and discharge will be dependent upon the speed of operation of shaft 28, the incline of the container 21, and the flow characteristics of the material being treated; and these factors will be chosen in practice to give a suitable discharge product.

It will be understood that particles of material being struck by the flaps 39 (12) will be driven outwardly toward lining 37 (2) where they will be acted upon by rubbing against other particles under pressure resulting from centrifugal forces, augmented by the forces of flying weight bars 42. The product will be a mixture of grains of material and finely reduced and loosened particles of the surface deposits which may readily be separated from the product by known classification methods, the desired product being collected in a comparatively pure state.

The apparatus described hereinabove has been found, in actual tests on used industrial core sand, and other foundry sands, to have a very beneficial effect and to assist greatly in the task of reconditioning such materials for reuse.

It will be understood that the apparatus particularly described and illustrated is by way of example only, and that the invention includes such modifications and equivalents as may readily occur to persons skilled in the art to which it appertains within the scope of the appended claims.

It is claimed and desired to secure by Letters Patent:

1. Apparatus for continuously milling granular material, comprising: a generally cylindrical container having a resilient liner providing a deformable work supporting surface; means for depositing said granular material on said work supporting surface at one end thereof; muller means rotatable within said container for rubbing said granular material against said work supporting surface and conveying said material longitudinally through said container; said muller means having at least one set of flexible, radially extending, circumferentially spaced flaps extending toward and engaging with said work supporting surface, each of said flaps being of a sufficient length that its extremity lies flat on said work supporting surface during rotation of said muller means; weight means associated with said extremities of said flaps to cause said extremities to depress successive portions of said work supporting surface, the restoration of the depressed portions of said work supporting surface causing said material to be thrown from said depressed portions; and means for rotating said muller means relative to said container.

2. Apparatus for continuously milling granular material, comprising: a generally cylindrical container having a resilient liner providing a deformable work supporting surface; means for depositing said granular material on said work supporting surface at one end thereof; muller means rotatable within said container for rubbing said granular material against said work supporting surface and conveying said material longitudinally through said container; means for inclining said container to obtain in cooperation with said muller means an optimum rate of feed and discharge for the kind of material to be milled; said muller means having at least one set of flexible, radially extending, circumferentially spaced flaps extending toward and engaging with said

work supporting surface, each of said flaps being of a sufficient length that its extremity lies flat on said work supporting surface during rotation of said muller means; weight means associated with said extremities of said flaps to cause said extremities to depress successive portions of said work supporting surface, the restoration of the depressed portions of said work supporting surface causing said material to be thrown from said depressed portions; and means for rotating said muller means relative to said container.
